UNITED STATES PATENT OFFICE.

ROBERT A. W. KRAMPITZ, OF VALDEZ, TERRITORY OF ALASKA.

ROCK-DRILLING MACHINE.

1,386,633.

Specification of Letters Patent.

Patented Aug. 9, 1921.

Application filed February 12, 1920. Serial No. 358,247.

To all whom it may concern:

Be it known that I, ROBERT A. W. KRAMPITZ, a citizen of the United States, and a resident of Valdez, Territory of Alaska, have made certain new and useful Improvements in Rock-Drilling Machines, of which the following is a specification.

My invention relates to rock drilling machines.

10 An important object of my invention is to provide a rock drilling machine in which the power may be applied direct to the drill through a positive mechanical train to impart uniform, constant and efficient operative movements to the drill.

Another important object is to prevent severe, unusual and destructive stresses from being set up in the drill and associated mechanism by automatically releasing the power when the drill is jammed, caught or otherwise held against its normal operative movements and cannot cut its way clear and to automatically resume and maintain the application of power when the reactive forces opposing the operative movements of the drill are approximately normal.

Another object is to provide an improved mounting for the drill and its operating mechanism well adapted to meet the rigorous requirements of this character of work.

Another object is to provide an improved rock drill of simple and durable construction, reliable in operation and comparatively inexpensive in manufacture.

35 Other objects and advantages reside in the certain novel features of the construction, arrangement and combination of parts, which will become apparent as the description proceeds, reference being had to the accompanying drawings forming part of this specification, and in which:—

Figure 1 is a side elevation of my improvement.

Fig. 2 is a sectional view on line 2—2 of Fig. 1.

Fig. 3 is a sectional view on line 3—3 of Fig. 1, looking in the direction of the arrow.

Fig. 4 is a plan view.

50 Fig. 5 is a sectional view on line 5—5 of Fig. 4.

Fig. 6 is a fragmentary view of the saddle, the supporting rods and feed screw being shown in section.

Fig. 7 is a detailed view in vertical section of the drill stock and drillstock bearing and associated structure.

Fig. 8 is a front elevation.

Referring to the drawings, it will be seen my invention comprises a column 10, which may be of any conventional and well known construction. A clamp 11 is mounted upon the column 10 and is adapted to be secured in adjusted position on the column by means of a clamp screw 12 or the like. Integral with the clamp member 11 and extending outwardly and upwardly therefrom is the clamp arm 13 and the outer end of the clamp arm 13 has formed integrally therewith a saddle 14, as shown in detail in Fig. 6. The saddle 14 is provided with spaced longitudinal journals therethrough, as indicated at 15, and these journals preferably lie in the same horizontal plane. Approximately midway between the journals and preferably a slight distance below the same, the saddle is provided with a longitudinal opening 14' therethrough. The saddle is adapted to support the rock drill, as will be hereinafter more fully described.

80 A main frame 16 has formed at its front end a longitudinal bearing 16' and also at the front end immediately to the rear of the bearing is provided a depending front frame extension 17. The rear of the main frame is 85 provided with spaced vertical bearings 18, the axes of which are alined and preferably at right angles to the axis of the longitudinal bearing 14'. The lower of the spaced bearings 18 has integrally formed therewith 90 a rear depending frame extension 19, which is substantially U-shaped as shown in Fig. 1. A pair of spaced supporting rods 20 is provided and each of the supporting rods 20 has its front end secured in the front frame 95 extension 17 and its rear end secured in the rear frame extension 19, the portion of each rod lying between the front and rear frame extensions being slidably mounted in the journals 15 of the saddle 14.

100 A swinging auxiliary frame 21 has a vertical bearing 22 disposed between the spaced bearings 18 to the rear of the main frames 16. The upper end of the auxiliary swinging frame 21 is provided with spaced horizontal bearings 23.

105 A crank shaft 24 is journaled in the bearings 18 of the main frame and the bearing

22 of the auxiliary swinging frame and the crank shaft in this manner serves as the pindle for the auxiliary swinging frame. The crank shaft 24 carries at its upper end 5 a driven bevel pinion 25, and its lower end carries a crank disk 26 to which the crank pin 27 is secured. The driven pinion and the crank disk in addition to serving the functions to be hereinafter fully described, 10 act to maintain the crank shaft in proper position.

For securing the desired adjustment of the auxiliary swinging frame 21 and maintaining the auxiliary frame in this adjustment 15 a worm segment 28 is preferably integrally formed with the bearing 22 of the auxiliary frame. A worm 29 is journaled in bearing plates 30 which are secured to the main frame 16 and the squared ends 31 20 of the worm 29 are adapted to coöperate with an operating tool for effecting the desired adjustment of the auxiliary frame. The irreversibility of the worm arrangement 25 effects the maintenance of the auxiliary frame in adjusted position.

A drive shaft 32 is journaled in the horizontal bearings 23 of the auxiliary frame and the drive shaft receives its motion from any suitable source of power not shown, by 30 means of a flexible shaft or a telescopic shaft and universal couplings of conventional construction (not shown). Mounted on the inner end of the drive shaft 22 is a bevel drive pinion 33 having integral therewith 35 a sleeve 34, the inner end of which is provided with 45 degree teeth 35. The driven pinion and its sleeve are loose on the shaft 32, but by virtue of the fact that the drive pinion 33 is in mesh with the driven pinion 40 25, and that the rear face of the pinion bears against the forward bearing 23, the pinion and its sleeve 34 are prevented from being moved longitudinally with respect to the drive shaft. A slidable clutch collar 36 45 is splined to the drive shaft 32 by means of a slot 37 through the shaft and a cross pin 38 secured in the collar and extending through the slot, and this clutch collar is provided with 45 degree teeth as indicated 50 at 39, which are adapted to coöperate with the 45 degree teeth 35 of the sleeve of the drive pinion to normally constrain the drive pinion to motion with the drive shaft. A compression coil spring 40 is mounted on 55 the drive shaft, and has one end abutting the rear bearing 23 and the other end bearing against the slidable collar 36 to maintain the teeth of the collar in engagement with the teeth of the sleeve of the drive frame. It is obvious that unless the resistance 60 to the motion of the drive pinion exceeds the predetermined point (which point may be determined by the strength and compression under which the coil spring acts)

the drive pinion is constrained to rotate 65 with the drive shaft and when this resistance or load on the drive pinion exceeds this predetermined point, there is a relative slip of the teeth of the collar with respect to the teeth of the sleeve of the drive pinion 70 so that the motion of the drive shaft is not communicated to the drive pinion.

The drill stock 41 is mounted for reciprocatory movement in the longitudinal bearing 16' of the main frame, and this drill stock 75 has formed at its outer end a drill chuck 42 for receiving the drill tool 43 which may be of any conventional construction. The rear end of the drill chuck is provided with axial bore 44 therein of relatively great diameter and an axial bore 45 of reduced diameter with respect to the radial bore 44, and which communicates at one end with radial bore 44. A drill rod 46 has at its inner end a head 47 mounted for a limited reciprocatory movement in the axial bores 44 and 45. The drill rod through the head 47 is of course 80 connected to the drill stock by means of a cushioned connection consisting of a coil spring 48 disposed in the bore 45 between 85 the inner end of the bore and the head 47 of the drill rod, and a coil spring 49 disposed in the bore 44 between annular plates 50. The annular plates 50 as well as the coil spring 49 is mounted on the drill rod and 90 the inner annular plate abuts against the head 47 of the drill rod while the outer annular plates abuts against a cap 51 threaded on the drill stock and provided with a central opening 52 through which the drill rod 95 100 operates. It is apparent that on the forward stroke of the drill rod the spring 48 interposes its resiliency between the drill rod and the drill stock and that on the return stroke the spring 49 interposes its resiliency between the drill rod and the drill stock. The inner end of the drill rod 46 105 is connected preferably by means of a threaded shank socket connection 53 to the cross head 54, which in turn is connected by 110 the connecting rod 55 with the crank pin 27 of the crank disk 26.

Common means are provided for feeding the drill and for imparting the desired turning movements to the drilling tool, and consists of a feed shaft 56 having its front end rotatably mounted in the frame extension 18, and its rear end rotatably mounted in the frame extension 19 and carrying intermediate said frame sections a feed screw 115 120 57; the feed screw 57 extends through the opening 14' of the saddle and coöperates with a nut 58 fixed to the saddle and having its opening alined with the opening 14'. A hand crank 59 is provided for imparting 125 the desired movement to the feed screw 57. The end of the feed shaft adjacent to the frame extension 17 and gear wheel 60 is

keyed and the gear wheel 60 is meshed with a gear wheel 61 having inner or radial projections 62 mounted in longitudinal slots 63 formed in the drill stock 41 to constrain the 5 drill stock to rotary motion with the gear 61, while permitting relative rectilinear motion of the drill stock with relation to the gear wheel 61. The gear wheel 61 is constrained against rectilinear motion by being 10 mounted between the front frame extension 17 and a depending annular collar abutment 63, preferably formed integral with the main frame, which is internally threaded as shown. A bushing 64 is threaded in 15 said annular collar and its inner end adjustably abuts the gear wheel 61, as shown in Fig. 7. The gear wheels 60 and 61 are preferably so proportioned that for every turn 20 of the feed screw the drill stock is turned twice.

In practice the saddle having been secured in desired position by means of the clamp and column and power applied to the drive shaft 32, motion is transmitted through the drive 25 pinion 33, driven pinion 25, crank shaft 24, crank disk 26, and its pin 27 to the connecting rod 55 which imparts reciprocatory motion to the drill rod 46. Drill rod 46 through its cushioned connection imparts 30 reciprocatory motion to the drill stock 41 and consequently to the drill tool 43. The hand crank 59 is turned as desired to advance or feed the entire main frame and consequently the drilling tool and this automatically effects the turning movement of 35 the drill tool as heretofore described.

If the drilling tool becomes jammed, caught or is otherwise held against its normal operative movement and cannot cut its 40 way clear, the power applied through the drive shaft 32 would, if communicated positively, set up destructive stresses in the drilling tool and its associated mechanism tending to rupture or distort the same, but in the 45 present invention this does not occur as when the drill is caught or jammed the reactive force to the operative movements of the drill is of course greatly increased and this results in a greater resistance of load 50 of motion of the drive pinion 33 with the consequent relative slip or movement between the teeth of the sleeve of the drive pinion and the teeth of the clutch collar, and motion is not then communicated to 55 the drive pinion and therefore the drilling tool is not forced to partake of reciprocatory motion while so jammed, caught or held that a forced reciprocation would involve destruction, breakage, rupture, or distortion of the drilling tool or its operating 60 mechanism or associated structure. Consequently it is impossible for the stresses in the drilling tool or in any of its operating mechanism of associated parts to exceed

a predetermined point which point is of course established within the range of stress that the several parts are adapted to bear.

Moreover, as the crank shaft 24 constitutes the axis of swing of the auxiliary frame, the driven pinion 25 has its axis lying 70 in the axis of the crank shaft and the drive shaft 32 and its pinion 33 are carried on the auxiliary frame to swing about the crank shaft as its axis, the pinions 25 and 33 meshing in all positions of the auxiliary frame 75 with respect to the main frame and power may be transmitted thereto and therefore to the drilling tool irrespective of the location of the source of power with respect to 80 said main frame.

Again, the main frame, frame extension, supporting rods, saddle, etc. define a substantially inclosed space in which the operating parts partaking of movements of relatively large amplitude function and which 85 being effectively isolated are guarded while being immediately accessible for purposes of adjustment, repair, etc. Furthermore, this particular mounting gives not only great strength, and an adaptability for ready and 90 easy adjustment, but also a high degree of balance.

I claim:—

1. A rock drill of the character described comprising a main frame having a longitudinal bearing at its forward end and spaced vertical bearings at its rear end, an auxiliary swinging frame having a vertical bearing aligned with and adapted to be disposed between the spaced vertical bearings of said 100 main frame, a crank shaft mounted in the vertical bearings of said frames and constituting the axis of swing of said auxiliary frame, means for imparting motion to said crank shaft, a drill stock mounted for reciprocatory motion in the longitudinal bearing of said main frame, and means connecting said crank shaft and said drill stock. 105

2. A rock drill of the character described comprising a main frame having spaced 110 aligned vertical bearings at its rear end, a swinging auxiliary frame having a vertical bearing adapted to be disposed between the spaced bearings of said main frame, and means for imparting swinging motion to 115 said swinging frame and maintaining the same in adjusted position including a worm segment integral with said swinging frame and a worm mounted upon said main frame in mesh with said worm segment, all as and 120 for the purposes set forth.

3. In a rock drill of the character described, a drilling tool, means for reciprocating said drilling tool, a drive shaft, a drive pinion for actuating said reciprocating 125 means having a sleeve provided at its outer end with teeth and loosely mounted on said drive shaft, a slidably collar splined on said

drive shaft and having one end provided with teeth adapted to be engaged with the teeth of said drive pinion sleeve for normally constraining said drive pinion to motion with said drive shaft and permitting motion of said drive shaft relative to said drive pinion when the resistance to the reciprocation of said drilling tool exceeds a predetermined point, and a spring for maintaining the teeth of said collar in engagement with the teeth of said pinion.

4. In a rock drill of the character described, a drill stock having an axial bore at its inner end, a drill rod having a head adapted to operate in said bore and a cushioning connection between said drill rod and said drill stock including a coil spring between said drill rod head and the inner end of said bore, an annular plate disposed against the outer face of said drill rod head, a cap closing the outer end of said bore and a coil spring between said plate and

said cap, all as and for the purposes set forth.

5. A rock drill of the character described comprising a support provided with spaced journals therein, a main frame having a longitudinal bearing on the under side of its forward portion and having a depending front extension below said longitudinal bearing and a depending rear extension of U-shaped form, spaced supporting rods fixed to said front frame extension and to the lower leg of the rear U-shaped extension and carried by the journals of said support, a drill stock mounted for reciprocatory movement in such longitudinal bearing, and means for reciprocating said drill stock, including a crank mechanism operating between the legs of the U-shaped extension and a connecting rod lying below said main frame and above the lower end of the frame extension in all phases of its movements.

ROBERT A. W. KRAMPITZ.
